[57] ABSTRACT

Lanolin derivatives essentially comprising esters of lanolin alcohol with lactic acid and higher fatty acids are provided. The derivatives are prepared by direct reaction of lanolin alcohol with the higher fatty acid. The lanolin derivatives disclosed are especially adapted for use as essential or advantageous ingredients of various cosmetic compositions.

2 Claims, No Drawings

LANOLIN DERIVATIVES ESSENTIALLY
COMPRISING ESTERS OF LANOLIN ALCOHOL
WITH LACTIC ACID

This invention relates to new compounds which are derivatives of lanolin. More particularly the invention relates to esters of lanolin alcohols with lactic acid and higher fatty acids.

As is well known, lanolin (frequently termed "wool wax" or "wool fat") is extensively used in cosmetic compositions, as well as in various other products, including pharmaceutical preparations, textile lubricants, textile softening agents, etc.

Lanolin is generally considered to consist of a mixture of naturally formed esters, derived from higher alcohols and higher fatty acids. A highly valuable constituent of lanolin is cholesterol.

The alcohol and acid components of lanolin have become of increasing importance in recent years. Processes for obtaining these two components by saponifying lanolin and then separating the lanolin alcohols from the lanolin acids are quite well known.

A recently described process for such separation is referred to in an article by Van Dam which appears at pages 37-40, Vol. 84 of American Perfumer and Cosmetics (August, 1969). As there described, the process entails first saponifying the wool wax (as by alcoholic alkali), and separating the alkaline soaps of the lanolin acids from the unsaponifiable portion containing the lanolin alcohols.

The lanolin alcohol portion of lanolin wax is believed to be of the following composition (determined by column chromatography):

Cholesterol	32.5%
Isocholesterol	44.2%
Aliphatic alcohols	14.7%
Aliphatic diols	3.2%
Hydrocarbons	0.9%

According to the procedure described by Van Dam, cholesterol is separated from the unsaponifiable portion, leaving in solution the residual wool wax alcohols (a mixture of aliphatic alcohols), trimethylsterols and some C₂₇-cyclic alcohols.

The alkaline soaps of the lanolin acids may be acidified to thereby recover the lanolin acids.

The lanolin acids obtained by acidification of the alkaline soaps thereof, and the relative amounts thereof composing the lanolin acid fraction of wool wax, are believed to be as follows:

	%
n-alkanoic acids	7
iso-alkanoic acids	23
ante-iso-alkanoic acids	30
hydroxy-alkanoic acids	28
unidentified	12

Lanolin alcohols and lanolin acids separated from wool wax and isolated from each other by the procedure above described are of technical grade.

Previous efforts to produce fatty acid esters of wool wax alcohols by esterification of lanolin alcohol with such acids have resulted in producing commercially unsatisfactory yields of the esters, and in producing esters which fail to exhibit desired properties.

The principal object of the invention is to provide new compounds constituting derivatives of lanolin.

More specifically, it is an object of the invention to provide derivatives of lanolin which are lactic acid esters and fatty acid esters of lanolin alcohols.

Another object of the invention is to provide a method for the preparation of such esters.

Still another object of the invention is to provide a method for producing, in satisfactory yields, compounds constituting improved lactic acid esters and fatty acid esters of lanolin alcohols.

A still further object of the invention is to provide improved cosmetic and other industrial compositions utilizing lactic acid and fatty acid esters of lanolin alcohols as an active ingredient thereof, whereby to impart various desirable properties and advantages to such compositions.

The aforementioned objects of the invention may be achieved by the esters of lanolin alcohol herein described, produced by the esterification procedure hereinafter more fully set forth.

Briefly stated, the lanolin alcohol esters of the present invention may be produced by the direct reaction of refined lanolin alcohol with lactic acid or with one of the enumerated fatty acids. The lanolin alcohol utilized is the entire wool wax alcohol fraction containing all of the sterols (including cholesterol) isolated from the wool wax.

In accordance with the invention, not only does the lanolin alcohol used in forming the esters hereof consist of the entire alcohol fraction of wool wax, but it is further characterized by being refined from the technical lanolin alcohols normally isolated from wool wax.

By the term "refined" as employed herein to refer to the lanolin alcohols utilized in producing the esters of the present invention, is meant lanolin alcohols resulting from a distillation and deodorization treatment of technical lanolin alcohols. A preferred form of such treatment is described in the U.S. Pat. Nos. to Richey et al., 3,272,850 and 3,272,851.

The aforesaid treatment, briefly stated, consists of subjecting the technical lanolin alcohols, in the form of a slowly moving, whirling or so-called "wiped film" of relatively minute thickness, to contact with a heated surface while held under vacuum, and simultaneously subjecting the thus heated film to the stripping action of a counter-current flow of steam.

The described action apparently results in so modifying and deodorizing the technical lanolin alcohols as to enable them to react in a more desirably effective manner in the esterification reaction with the herein-mentioned acids, and thus to yield the lanolin alcohol esters of the invention.

Preferably, the thus refined lanolin alcohol is also treated to bleach or decolorize the same, following the refining treatment.

The fatty acids employed in esterifying the refined lanolin alcohols to produce the esters of the present invention may be selected from among the fatty acids of 10 or more, preferably 12 to 18, carbon atoms.

In addition to the esters made with the aforementioned fatty acids, lanolin alcohol esters embodying the invention may be made with lactic acid.

The acids employed for esterifying the refined lanolin alcohols in accordance with the invention preferably include lauric, myristic, palmitic, isostearic and oleic, as well as lactic acid.

As above indicated, the esters are formed by direct reaction of the refined lanolin alcohol with the selected acid, without necessity of using a solvent during the reaction.

In the practice of the esterification method of the invention, it is preferred that the reaction be performed in the presence of a suitable catalyst. To that end, para-toluenesulfonic acid in the amount of about 0.5 gram per mol of lanolin alcohol has been found to be suitable.

The lanolin alcohol and the selected acid are mixed, the catalyst then added, and the mixture heated. Nitrogen sparge was utilized, as was also stirring of the mixture. Temperature ranges were generally from 85°C to 170°C. Water of reaction was removed through a suitable condenser, and the reactions were continued until an acid value of 15 or less was attained. Esterification was achieved within a heating time of from approximately four to eleven hours.

Upon completion of the esterification, the reaction products were washed to remove excess acid. For that purpose, the compounds were dissolved in benzene and a calculated amount of a 10% solution of potassium hydroxide was added. After the formed emulsion had separated, the benzene layer was washed with saturated salt water until neutral. Where necessary, or desirable, the color of the compound was lightened by solution in isopropanol and treatment with charcoal. The compounds are thereby rendered ready for testing and use.

The esters of lanolin alcohol produced with the above-named acids, together with the temperature range and heating time utilized in the preparation thereof, respectively, are as follows:

TABLE I

Ester	Temp. range (°C)	Heating Time (Hours)
Lanolin lactate	80° - 135°	4
Lanolin laurate	85° - 160°	10
Lanolin myristate	110° - 200°	7½
Lanolin palmitate	135° - 170°	5½
Lanolin isostearate	140° - 175°	6
Lanolin oleate	70° - 190°	11

As hereinabove indicated, the esters embodying the invention are prepared by esterifying refined lanolin alcohols containing the cholesterol and other sterol components of wool wax, with the named acids. The resulting esters are in sharp contrast to the compounds referred to in the above-mentioned article by Van Dam, formed by esterification of so-called wool wax alcohols LO. The expression "wool wax alcohol LO", as indicated by Van Dam, refers to the residual wool wax alcohols remaining after the cholesterol has been removed.

Herebelow are set forth examples of a number of lanolin esters embodying the invention, together with the method for preparing the same.

EXAMPLE I

LANOLIN LAURATE

200.3 grams (1m) of lauric acid, 362 grams (1m) of refined lanolin alcohol and 0.5 gram para-toluenesulfonic acid were charged into a suitable reaction vessel having four necks. Provision for stirring the mixture

was made, a nitrogen sparge was attached, and a condenser for water take-off was also hooked up.

Heat was applied until the reactants were melted, whereupon agitation was initiated. Water began to appear and be driven off at about 115°C. Heating was continued for ten hours, maintaining the reaction mixture at a temperature of from 115°C to about 165°C. A total of 14 cc. water was obtained. Aliquot portions of the reaction were taken until an acid value of 15 was reached. 100 grams of the reaction product were dissolved in 300 cc. of benzene. This solution was shaken with 40 cc. of a ten percent aqueous solution of potassium hydroxide, the benzene layer was separated from the aqueous layer and washed with three 100 cc. portions of water. Benzene was stripped from the washed solution in vacuo, thereby yielding the lanolin laurate. The product was then decolorized by means of isopropanol as solvent, and charcoal as the decolorizing agent.

20

EXAMPLE II

LANOLIN PALMITATE

724 grams (2m) of refined lanolin alcohol, 512 grams (2m) of palmitic acid and 1 gram of para-toluenesulfonic acid were charged to a four-neck reaction vessel fitted with a nitrogen sparge, a water take-off condenser, and a stirrer. After melting of the components of the reaction mixture in the vessel through the application of heat, water was evolved at 140°C. Heating of the mixture was continued for five and one-half hours, during which the temperature of the mixture maintained was in the range of from 135°C to 180°C. A total of approximately 17 cc. of water was obtained in the reaction, and the final acid value was 15.4. 100 grams of the reaction product were dissolved in benzene, as in Example I, and the solution shaken with alkali removal of excess acid, following which the benzene layer was separated from the aqueous layer and the benzene distilled in vacuo. After elimination of the benzene, the product could be crystallized readily from solution in isopropanol.

EXAMPLE III

LANOLIN ISOSTEARATE

181 grams (½m) of lanolin alcohol, 142.2 grams of isostearic acid, 1 gram of para-toluenesulfonic acid, and 300 cc. of benzene were charged into a suitable reaction vessel, fitted with a Dean Stark trap, with a condenser and a stirrer. The reaction mixture in the vessel was refluxed and the amount of water accumulated in the Dean Stark trap was recorded. Heating of the mixture at reflux conditions was continued for approximately 21 hours, until 8.1 cc. of water was removed. 12 grams KOH in 600 cc. of water were added in a separatory funnel and the layers were separated. The benzene layer was washed with two 100 cc. portions of water, and the benzene was then stripped under vacuo.

The foregoing examples of procedure for preparing certain of the esters of lanolin alcohol embodying the invention, should make it evident that the same or similar procedure will be suitable for the preparation of others of the esters of lanolin alcohol embodying the present invention.

As will be evident to those skilled in the art, the precise physical constants of the esters embodying the invention will vary to some extent, depending primarily upon the properties of the starting materials.

Since the lanolin alcohols employed in preparing the esters hereof, consist, as above indicated, of the entire unsaponifiable fraction of the wool wax, i.e., the unsaponifiable part without cholesterol having been removed therefrom, the resultant esters are characterized by desirable properties not exhibited by esters produced by esterification of so-called "wool wax alcohol LO," i.e., residual lanolin alcohols remaining after separation of cholesterol from the unsaponifiable fraction of wool wax, with the same acids.

The preparation of the lanolin lactate differed from that utilized for preparation of the other esters listed in that the reaction of the lanolin alcohol and the lactic acid was carried out under vacuum (water pump — 54 mm.). Also, with respect to this ester, the procedure utilized for washing the same differed from that utilized for the washing of the other esters listed, in that in this instance the washing was performed with water only.

In Table B herebelow are set forth the physical constants for a number of the preferred acid esters of lanolin alcohol embodying the invention.

TABLE B

	Acid Val.	M.P. °C	Color-Gardner	Sap. Val.	Water Absorp.	OH Val.	I ₂ Val.
Lanolin Lactate	1.2	42.1	9½-10	125.5	340	118.9	29.5
Lanolin Laurate	.24	47.3	4-5	98.1	184	7.0	28.3
Lanolin Myristate	.61	41°	9½-10	102.7	96	12.0	30.7
Lanolin Palmitate	.25	49.7	2-3	88.8	102	7.5	29.6
Lanolin Isostearate	.40	Semi-liquid	12-13	82.9	198	9.9	27.0
Lanolin Oleate	.75	Liquid	11-12	83.9	120	7.6	55.3

Reference has hereinabove been made to the fact that the lanolin esters of the invention possess properties which render them especially suitable and advantageous for use in the preparation of cosmetic compositions. In the Examples herebelow, formulations for a variety of cosmetic compositions are set forth, wherein these esters constitute essential ingredients of the formulations. These formulations are as follows:

EXAMPLE 1

W/O Emulsion

Phase A	W/W%
Beeswax, white	16
Mineral oil (70 visc.)	50
Lanolin oleate	2
Phase B	
Deionized water	31
Borax	1

In preparing the composition of this formulation, phase A and phase B are each heated to about 75°C., and phase A is added to phase B. The composition is then cooled to about 30°C. It is a simple water-in-oil type emulsion.

As will be noted from the above formulation, the lanolin oleate shows significant water-in-oil emulsifier

properties at a relative-low concentration and without necessity for the presence of any auxiliary emulsifier. The composition is non-greasy and serves as an excellent base for cleansing creams and so-called night creams. It very effectively removes lipstick and eye make-up by use of tissue.

10 Vanishing Cream (O/W)

Oil Phase	W/W%
Stearic acid (T.P.)	15.00
Tegacid, Reg.	2.00
Myristyl Alcohol	0.50
Mineral Oil (70 visc.)	8.00
Isopropyl palmitate	3.00
Lanolin Myristate	5.00

Water phase	W/W%
Deionized water	55.40
Triethanolamine	1.00
Methyl Paraben	0.10
Propylene glycol	10.00

35 This vanishing cream composition is characterized by its ability to spread easily on the skin, and to leave a semi-matt film; also by ability to aid in retention of facial powder.

40 The following formulations are for enriched moisture creams, each made with a higher fatty acid ester of lanolin alcohol, embodying the invention:

45 Moisture Cream

Phase I	W/W%	W/W%
Mineral Oil (70 visc.)	13.00	13.00
Emersol 132 (stearic acid)	3.00	3.00
Glyceryl monostearate	3.00	3.00
Spermaceti wax	4.00	4.00
Propyl Paraben USP	0.10	—
Lanolin laurate	10.00	—
Lanolin palmitate	—	10.00

Phase II	W/W%	W/W%
Deionized water	55.35	55.35
Propylene glycol	5.00	5.00
Carbopol 940 (3% aq. sol'n)	5.00	5.00
Methyl Paraben	0.15	0.15
Triethanolamine, 85-87%	1.00	1.00

Phase III	W/W%
Perfume	0.40

65 These two formulations provide moisture creams which possess long term thermal stability, and have excellent gloss, smoothness with a slightly oily-feel, and are non-tacky and cosmetically "elegant."

The formulations shown in the following tabulation illustrate several lipstick compositions utilizing lanolin lactate or one of the higher fatty acid esters of lanolin alcohol embodying the invention:

Lipsticks	W/W%	W/W%	W/W%
Candelilla wax	5.00	5.00	5.00
Carnauba wax	2.00	2.00	2.00
Ozokerite	1.50	1.50	1.50
Spermaceti	1.50	1.50	1.50
Myristyl lactate	4.00	4.00	4.00
Mineral oil, 70 visc.	5.00	5.00	5.00
Tenox 2 (20% butylated hydroxyanisole; 6% propyl gallate; 4% citric acid; 70% propylene glycol)	0.30	0.30	0.30
Yellow beeswax	8.00	8.00	8.00
"Nodorlan" (lanolin — purified according to process of U.S. Pat. No. 3,272,850)	10.00	10.00	10.00
"Lantrol" (lanolin fraction — prepared according to the process of U.S. patent 2,758,125 and purified according to process of U.S. patent 3,272,850)	5.00	5.00	5.00
Perfume	0.75	0.75	0.75
25% castor oil sol'n of TiO ₂	31.95	31.95	31.95
C-15004 (brilliant scarlet barium lake dye)	6.00	6.00	6.00
C-76001 (permanent orange, barium lake dye)	6.00	6.00	6.00
3621 (pale bromo dye)	3.00	3.00	3.00
Lanolin Myristate	10.00	—	—
Lanolin Lactate	—	10.00	—
Lanolin Oleate	—	—	10.00
	100.00	100.00	100.00

The ester of lanolin alcohol and lactic acid has been found to possess properties which enable it to impart advantageous characteristics not only to lipstick compositions, but to other cosmetic compositions as well. Illustrating such cosmetic compositions are those of the formulations shown below:

No. 1 O/W Ointment Base

Oil Phase A	W/W%
Lanolin lactate	19.24
Petrolatum	16.00
Propyl Paraben	0.10
Water Phase B	
Sodium lauryl sulphate	0.66
Propylene glycol	12.00
H ₂ O	51.90
Methyl Paraben	0.10
	100.00

Phase A is heated to 75°C., and phase B is heated to 75°C. Phase A is added to phase B at 75°C. The resultant composition is then cooled to 30°C.

The resultant composition is an ointment of heavy lotion-like character. It exhibits a relatively high degree of gloss and sheen and a desirable cosmetic "look". Its phase properties enable it to be packaged in and used from either a jar or other container.

No. 2 Absorption Base

	W/W%
Mineral oil	31.9
Lanolin lactate	38.0
Wool wax alcohol	10.0
Petrolatum	16.0
Paraffin	4.0
Propyl Paraben	0.1
	100.0

The mixture of the above ingredients is heated until it is uniform (80°C.), and is then cooled to room temperature. In the foregoing formulation, the lanolin lactate functions as a highly effective emulsifier when

incorporated with the other ingredients. Aside from constituting a desirable cosmetic formulation, this composition exhibits properties enabling it to serve as an excellent emulsifier of the water-in-oil type and as a stabilizer for various creams and lotions.

Oil phase A is heated to 75°C., as is the water and

No. 3 Zinc Oxide Ointment

	W/W%
Zinc oxide	40.0) C
Talc	5.0)
Petrolatum	33.0) A
Mineral oil	10.0)
Lanolin lactate	7.0) B
Water	5.0)

the latter is added to the former. The zinc oxide and talc are then slowly added, and the composition is allowed to cool to room temperature. It exhibited a desirable white color and a very good appearance and a high gloss.

No. 4 Cake Mascara

	W/W%
Carnauba wax	10.0
Beeswax	10.0
Glycerol Monostearate, (non-self emulsifying)	10.7
Stearic acid (3x)	20.0
Sodium stearate (C-1)	4.0
Propyl Paraben	0.1
Lanolin lactate	25.0
Triethanolamine	10.0
Cab-O-Sil M-5 (silicon dioxide, fine form sub-micron size)	0.2
Carbon black	10.0
	100.0

The first seven of the above-listed ingredients are melted together at a temperature of 80-90°C., and the TEA is added thereto. The Cabosil and carbon black are mixed with each other and added to the mixture of the other ingredients, and the total mixture is stirred for approximately 15 minutes. It is then poured into suitable pans at 80-85°C., for solidification and cooling to room temperature. The product exhibits excellent spreading properties, and the spread film possesses quick drying and good water-repellant qualities.

No. 5	Lip Ice	W/W%
Carnauba wax	3.6	15
Castor oil	72.0	
Ozokerite	7.0	
Candelilla wax	6.0	
Propyl Paraben	0.1	
Lanolin lactate	11.2	
Camphor	0.1	20
	100.0	

The mixed ingredients are heated to 85°C., and when uniform the heated mixture is poured into lipstick molds. The resultant lip ice is characterized by imparting a good softening feel to the lips and by its good application qualities.

No. 6	Hair Pomade	W/W%
Petrolatum	50.0	30
Lanolin lactate	15.0	
High Viscosity Mineral oil	30.0	
PEG monostearate	5.0	
	100.0	

The ingredients are mixed, the mixture is heated until uniform and is poured into jars at 65-70°C. The tests of this composition show that the lanolin lactate present therein enables the composition to yield an improved and superior hair groom, as compared to the same composition utilizing fatty alcohol

(e.g., cetyl) lactates and not lanolin lactate. The hair grooming product above set forth is more homogenous and without substantial tackiness. It imparts a very good sheen to the hair, and one in which the presence of petroleum in the composition is not discernible by "showing through".

No. 7	Barrier Cream	W/W%
Oil phase		
Stearic acid (3x)	3.5	
Span 60	2.0	
Tween 60	1.5	
Lanolin lactate	10.0	
Propyl Paraben	0.10	
Water phase		
Carbopol 934	0.25	
Water	q.s.	
Triethanolamine	0.25	
Propylene glycol	10.0	
Methyl Paraben	0.10	
	100.00	

The ingredients of the oil phase are mixed, and this phase is heated to 75°C. The Carbopol is added slowly to the water phase under good agitation. This phase is heated to 75°C. and the other three ingredients of this phase are added thereto. The oil phase is then added to the water phase at 75°C. Upon completion of formation of the emulsified product, it is cooled to 30°C. The resulting cream exhibits a substantially improved capacity for serving as a barrier against water, as compared to barrier cream formulations heretofore proposed.

What is claimed is:

1. A derivative of lanolin consisting essentially of an ester of a lanolin alcohol consisting of the entire wool wax alcohol fraction containing all of the sterols, including cholesterol, isolated from the wool wax, the acid fraction of said ester being derived from lactic acid.

2. The compound of claim 1, wherein said alcohol is refined lanolin alcohol.
